(57) CLAIM

The ornamental design for a cutlery set, as shown and described.

DESCRIPTION

FIG. 1 is a front, left and bottom perspective view of a first part of a cutlery set, showing my new design;

FIG. 2 is a front, right and top perspective view thereof;

FIG. 3 is a rear, left and top perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a front, left and top perspective view of a second part of a cutlery set;

FIG. 11 is a rear, right and bottom perspective view thereof;

FIG. 12 is a rear, left and top perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is a front, left and bottom perspective view of a third part of a cutlery set;

FIG. 20 is a front, right and top perspective view thereof;

FIG. 21 is a rear, left and top perspective view thereof;

FIG. 22 is a front view thereof;

FIG. 23 is a rear view thereof;

FIG. 24 is a left side view thereof;

FIG. 25 is a right side view thereof;

FIG. 26 is a top plan view thereof;

FIG. 27 is a bottom plan view thereof;

FIG. 28 is a front, left and bottom perspective view of a fourth part of a cutlery set;

FIG. 29 is a front, right and top perspective view thereof;

FIG. 30 is a rear, left and top perspective view thereof;

FIG. 31 is a front view thereof;
 FIG. 32 is a rear view thereof;
 FIG. 33 is a left side view thereof;
 FIG. 34 is a right side view thereof;
 FIG. 35 is a top plan view thereof;
 FIG. 36 is a bottom plan view thereof;
 FIG. 37 is a perspective view in the tiled configuration with the four parts together thereof; and,
 FIG. 38 is a perspective view in the used configuration with the four parts assembled together thereof.
